SLIP COVER

Estelle Gould, Chicago, Ill.

Application July 2, 1947, Serial No. 758,585

2 Claims. (Cl. 155—182)

1

This invention relates to improvements in so-called slip covers for use in the ornamental and utility covering of upholstered furniture pieces, i. e., chairs, sofas, etc.

More particularly, the invention has for its desiderata, to provide a unitary stock or "made up" type of slip cover of simple, economical and durable construction and design, capable of convenient and satisfactory installation on upholstered chairs which vary, to some extent, in design and size; moreover, to permit of smooth and snug arrangement and retention of the cover about and over the exposed surfaces of an equipped chair, irrespective of those seating or similar stresses to which said chair shall be subjected during its usage.

Additionally, it is an object of the invention to provide a slip cover of the above indicated character, which may be advantageously and satisfactorily installed on sofas and similar articles of furniture, notwithstanding differences (within a reasonable range) in design and size of the same.

Furthermore, it is an object of the invention to provide a slip cover constructed and designed in a manner to afford advantageous and beneficial upholstered furniture fit tolerances, and means operable in conjunction therewith, whereby when the cover is snugly and smoothly engaged over the back, sides, arms, etc., of an article of furniture, such engaged portions will be automatically "drawn" thereover to maintain said engagement, but at the same time, allow adequate self-adjustment or relative movement between stressed portions of the cover and adjacent portions of the article of furniture without subsequent wrinkling or disarrangement thereof, or portions thereof.

The foregoing, as well as other objects, advantages and meritorious teachings of my invention, will be in part obvious and in part pointed out in the following detailed disclosure thereof, when taken in conjunction with the accompanying drawings, it being understood that the form of the invention presented herein is a precise and what is now considered to be the better mode of embodying its principles, but that other modifications and changes may be made in specific embodiments without departing from its essential features.

In the drawings:

Figure 1 is a rear elevation of a sofa or like article of furniture, having my improved cover installed thereon, and wherein, the sofa back rearward side covering panel-like flap is frag-

2

mentally shown in an open or raised position.

Figure 2 is a fragmentary rear elevation of the construction shown in Figure 1, but wherein, said sofa back rearward side covering flap-like panel is in closed and connected position with relation to the sofa and the slip cover, and

Figure 3 is an enlarged vertical fragmentary section taken on the line 3—3 of Figure 2, looking in the direction in which the arrows point, showing the positioning of the sofa back rearward side covering flap-like panel with relation to the sofa back and the manner in which it is connected to the normally rearward portion of the slip cover.

15 Referring in detail to the drawings, the invention is particularly adaptable for installation and use on sofas, as indicated at S, and like furniture. Said illustrated type, generally, comprises a cover assembly including hood-like sofa side and arm envelopes 23 and 24, a back inner side panel 25 between said envelopes and extending from the sofa bottom upwardly over the back thereof, the usual sofa front panel (not shown), relatively opposed complementally formed hood-like sofa back end pieces 26 and 27, and a skirt 28, pleated or otherwise treated, for covering the lower portion of the sofa.

20 Portions of the envelopes 23 and 24, the end pieces 26 and 27, and the skirt 28, are extended or lapped about and over the rearward side of the sofa back and have their free ends or marginal portions aligned and contiguous (see Figure 1).

25 A sofa back or rearward side covering panel 29 is connected at and along its upper edge or end to the upper and rearward end of the panel 25 and to adjacent and underlying portions of the pieces 26 and 27. The length of the panel 29 is sufficient to cause its opposite end portions to overlap the inner and rearward portions of the pieces 26 and 27 when in a hanging or pendent position (see Figure 2).

30 35 40 45 A substantially U-shaped yoke 30, of appropriate depth, formed of suitable tape or like material, has the free and upper ends of its opposed legs connected, as at 31, to an intermediate (preferably medial) portion of the upper and rearward end of the panel 25 and normally hangs in approximate parallelism to the rearward side of the back of the sofa S (see Figures 1 and 3).

50 55 Webbing strips 32, or the like, are arranged adjacent and connected to the inner sides of the free and rearward end portions of the pieces 26 and 27 and the near upper portions of the en-

velopes 23 and 24 in parallel relation thereto. Grommets 33 are mounted, in correspondingly spaced relation, in the strips 32; also, grommets 34 are mounted in the opposite and lower corners of the yoke 30.

In order that the lower and free portion of the yoke 30 will be securely though adjustably anchored with relation to the rearward side of the sofa back, tapes 35, having strip-elastic loops 36 connected to their normally lower ends, are provided. The elastic loops are engaged over and about the rear legs L^a of the sofa S and their tapes 35 are obliquely extended toward the respectively adjacent corners of the yoke 30, whereupon, the tape free end portions are passed through certain of the yoke mounted grommets 34 and then tied or otherwise secured after the tapes and their loops have been sufficiently tensioned. Thus, it is seen that the lower and free end of the yoke 30 is secured; moreover, that a definite rearward stretching or tensioning of the panel 25 is effected, whereby the same will be tautly and smoothly disposed over the inner side of the back of the sofa S. At this point, it will be borne in mind that the lower end of the panel 25 has connection with the sofa bottom by being tucked between it and adjacent portions of the sofa back. Furthermore, attention is called to the fact that with stressing of said panel, as when seating or like loads are applied thereto, the elastic loops 36 of the connecting tapes 35 will permit of satisfactory auto-adjustment and compensation, and with discontinuance of such stresses, will immediately return the panel to its original relative position on the sofa back.

To effect longitudinal stretching or tensioning of the slip cover, i. e., whereby the envelopes 23 and 24, the panel 25 and the hoodlike sofa back end pieces 26 and 27, will be smoothly and tautly engaged over adjacent surfaces of a covered sofa, laces 37 are provided. Certain of the ends of each of said laces are engaged in the lowermost of the strip carried grommets 33 and are then passed inwardly of the rearward side of the sofa back through the remaining grommets 34 in the opposite corner portions of the yoke 30, from whence they are reversed and passed and have their free ends engaged through the remaining or uppermost grommets 33 in the aforesaid strips 32. The laces are then tied, as at 38; or otherwise secured after they have been pulled sufficiently taut of tension, to impart the above referred to longitudinal stretching or tensioning to the slip cover assembly members 23, 24, 25, 26 and 27.

With connection of the tapes 35 and laces 37, in a manner above explained, the panel 29 is then moved to its hanging or pendent position, as indicated in Figures 2 and 3 of the drawings. Since the opposite end portions of said panel overlie adjacent portions of the slip cover, as hereinbefore described, connection of said panel end portions to the latter is preferably effected by separable fastener elements, generally identified by the numeral 39, the companionate members of which are suitably arranged on and secured to appropriate portions of said panel 29 and the rearward and inwardly directed portions of the envelopes 23 and 24 and the sofa back end pieces 26 and 27. The positioning of the separable fasteners 39 on those parts to be interconnected thereby, is such as to ensure, with their connection, disposition of the panel 29 over the rearward side of the sofa back in a smooth, unwrinkled and sufficiently taut condition.

Should it be desired, the number of tapes 35

and laces 37 and their disposition or relativity with respect to the yoke 30, the sofa legs L^a, and the rearward and inner portions of the slip cover, may be varied, such as conditions or preference 5 may dictate, whereby to provide for the most satisfactory stretching and disposition of the slip cover assembly on and over an equipped sofa.

The herein disclosed improved slip cover may, 10 of course, be satisfactorily constructed from many different characters or types of fabrics or materials. Cretonnes, sail-cloth, knitted fabrics, such as Jersey cloth, plastic fabrics (rayons and the like), elasticised fabrics, etc., may be advantageously and effectually employed. Where 15 production of the slip cover is effected from stretchable or elasticised materials, it is manifest that the side arm envelopes; back, end covering pieces and panels, will have and be retained in 20 snug or close engagement with the covered surface of an article of furniture, and furthermore, that they will, because of their inherent elastic or auto-adjusting properties, remain free of wrinkles and like malformations and disarrangements.

I claim:

1. A slip cover for an article of furniture, comprising a cover assembly including opposed article side and arm envelopes, opposed article back-end covering pieces and a front-back panel between and connected to the envelopes and pieces, the free end portions of said envelopes and pieces being extendable inwardly and over portions of the rear side of the back of the article of furniture and arranged in spaced relation, a substantially U-shaped yoke connected at certain of its ends to an intermediate portion of the upper and rearward end of said front-back panel and adapted to normally hang therefrom, means for 35 adjustably connecting the opposite sides of said yoke to relatively opposed portions of the free end portions of the envelopes and pieces, longitudinally adjustable means connected to other portions of said yoke and detachably connectable to relatively opposed fixed portions of the article of furniture, a second panel connected at one end to the upper and rearward end of said front-back panel, the width of said second panel being sufficient to cover the space between said 40 free end portions of the envelopes and pieces and said U-shaped yoke, and means for detachably connecting portions of said second panel to adjacent portions of the free end portions of the envelopes and pieces.
2. A slip cover for an article of furniture, comprising a cover assembly including opposed article side and arm envelopes, opposed article back-end covering pieces and a front-back panel between and connected to the envelopes and pieces, the free end portions of said envelopes and pieces being extendable inwardly and over portions of the rear side of the back of the article of furniture and arranged in spaced relation, a substantially rectangular piece connected 45 at its upper end to an intermediate portion of the upper and rearward end of said front-back panel adapted to normally hang therefrom, laces engaging portions of the opposite sides of said rectangular piece and relatively opposed portions 50 of adjacent free end portions of the envelopes and pieces, the engagement of said laces with said adjacent free end portions of the envelopes and pieces being in vertically spaced relation above and below their engagement with the opposite sides of said rectangular piece, longitudinally

adjustable means connected to the lower and opposed corner portions of said rectangular piece and detachably connectable to relatively opposed fixed portions of the article of furniture below the lower and opposed corner portions of the rectangular piece, a second panel connected at one end to the upper and rearward end of said front-back panel, the width of said second panel being sufficient to cover the space between said free end portions of the envelopes and pieces and said rectangular piece, and means for detachably connecting portions of said second panel to adjacent portions of the free end portions of the envelopes and pieces.

ESTELLE GOULD.
